PLUMBING VENT VALVE

Robert R. Watts, Blue Springs, Mo., assignor to
Watco Plastics, Inc.

Filed May 11, 1972, Ser. No. 252,528

Term of patent 7 years

Int. Cl. D23—01

U.S. Cl. D23—19

Fig. 1.

Fig. 2.

Fig. 3.

Fig. 4.

FIG. 1 is a perspective view of a plumbing vent valve embodying my new design;

FIG. 2 is a top plan view thereof;

FIG. 3 is a side elevational view thereof, the opposite side being essentially the same; and

FIG. 4 is a bottom plan view thereof.

I claim:

The ornamental design for a plumbing vent valve, as shown and described.
